UNITED STATES PATENT OFFICE.

EMIL HENNINGS, OF CHICAGO, ILLINOIS.

BOX STITCHER.

Application filed November 19, 1919. Serial No. 339,082.

To all whom it may concern:

Be it known that I, EMIL HENNINGS, a citizen of the United States, residing at Chicago, in the county of Cook and State of Illinois, have invented a certain new and useful Improvement in Box Stitchers, of which the following is a full, clear, concise, and exact description, reference being had to the accompanying drawings, forming a part of this specification.

My invention relates to box stitchers and has to do more particularly with the provision of an improved form of construction of clincher block and support therefor co-
operative with the stitcher head for sealing fibre shipping boxes having an overlapping flange and flat box cover. One of the features of my invention is the provision of a stitcher for sealing fibre shipping boxes having an inturned flange around the edge of the box with a flat cover therefor and provided with a stitcher head for driving the metallic fasteners through the cover and flange, and a clincher block for insertion beneath the flange and having a support so constructed that the clincher block may be inserted beneath the cover and flange, the support being such that it may extend outwardly between the cover and flange and preferably beyond the edge of the cover so that the block may be moved along beneath the flange to stitch the overlapping portions of the cover and flange and seal the box around the entire edge, at the same time permitting the withdrawal of the block and support between stitches. When using the device to seal the cover to the flange of a filled box, the block and support are so constructed as to be capable of clinching the fastener without any additional support beneath the clincher block and at the same time permit movement of the block around the entire edge of the box including the corners thereof and then withdrawing the support and block from the box leaving the box sealed around the edge. Thus the box is sealed so as to prevent a ready opening thereof, the clinching of the metallic fasteners being such that a mutilation of the cover is necessary in order to open the box and an unwarranted opening thereof may be readily detected.

In the accompanying drawings I have shown the preferred form of my invention

together with the preferred type of box on which it is used and in which

Fig. 1 is a side elevation of a common form of stitching machine with my invention incorporated therein;

Fig. 2 is a side elevation of the clincher block and supporting means;

Fig. 3 is a front elevation of the same;

Fig. 4 is a plan view thereof;

Fig. 5 is a sectional view along the line 5—5 of Fig. 8 showing the position of the clincher block beneath the overlapping portions of the box;

Fig. 6 is a section along line 6—6 of Fig. 8;

Fig. 7 is a plan view of one form of box adapted to be operated upon; and

Figs. 8, 9, 10 and 11 show the different relative positions of the box and clincher block and support as the box of Fig. 7 is moved around in sealing the cover.

Referring now to the machine as shown in Figs. 1 to 6, my invention is adapted for use in applying metallic fasteners to fibre shipping boxes and for this purpose I have shown a well known type of machine adapted for driving the usual so called wire staple, the machine including the usual body portion 15 carrying the stapling head 16 operated by a belt driven pulley 17 controlled by a treadle 18. An adjustable table 19 is provided being carried by the body portion 15 and movable up and down by ordinary rack and pinion mechanism 20. Thus the machine may be accommodated for boxes of various thicknesses, the table 19 being movable relative to the clincher block so that it may be inserted beneath the cover of the box.

The preferred form of clincher block and supporting means therefor is shown more in detail in Figs. 2 to 6 and comprises a clincher block preferably in the form of a plate which need be only of such dimensions as to receive a staple clinching recess 22 and sufficiently rigid to take the impact of the staple and clinch it after it is driven through the box. The clincher block as shown here is of a comparatively thin construction so that it may be inserted beneath a cover securing flange on the shipping box and the contents thereof without effecting the loss of an undue amount of waste space. This clincher block 21 is preferably so supported

that it may be inserted between an inturned cover supporting flange and the cover without unduly separating them. The support is such that the cover and flange may meet above the clincher block as shown in Fig. 5 so as to be sealed in intimate contact when the fastener is driven therethrough. In the form of my invention as shown herein this construction includes a supporting element 10 23 which extends between the flange and cover, and is raised above the clincher block 21 by the upturned portion 24 so as to provide a space 25 through which the lower box portion may readily pass.

15 This portion 23 is also of a dimension and construction sufficiently rigid to support the block so as to take the impact as the staple is driven through and clinched, without additional support beneath the clincher block. 20 Also the support and block are preferably so shaped as to permit turning the box at the corners and placing fasteners through the overlapping portions thereat. In order to attach the clincher block and support to 25 the staple head an upturned bracket 26 is provided of a shape suitable to be securely fastened to the staple head in such a manner that the clincher block will be positioned beneath the staple driving element. It will, of course, be apparent that the clincher block and supporting means may be used in connection with various makes of stitchers or machines for driving various types of metallic fasteners, the shape, size, etc., of the bracket 26 being determined by the particular machine with which it cooperates.

30 In Fig. 7 I have shown a plan view of one form of box on which the device is designed to operate, this box being rectangular and provided with four sides each one of which has an inturned flange 27, and a flat cover 28, the box shown being of the usual fibre construction used for shipping containers of this kind.

35 In using the device for the purpose of sealing boxes of the type shown in Fig. 7, and assuming that the box has been filled and the flanges turned inwardly, it is placed upon the table 19 of the machine and the clincher block 21 inserted beneath the flange 27 as indicated in Fig. 8. The cover 28 is now placed upon the box and the flange 27 and cover 28 stitched together at A. (Fig. 7.) The box is now drawn toward the operator, moving the clincher block 21 along beneath the flange or inturned edge 27 of the box, the block support 23 moving along between the flange and cover. At proper points along the side, staples are driven 40 through the cover and flange to securely stitch them together. As the clincher block nears the first corner of the box the box is turned as indicated in Fig. 9 so as to place a staple through the overlapping portions at 45 B after which the box is turned still further so as to be in the position indicated in Fig. 10. This permits placing a staple at C through the overlapping portions. The next side is now drawn toward the operator and stitched and the box moved until it is sealed 70 all around, the staples being indicated at A, B, C and D to correspond with the markings of Figs. 8 to 11.

Now in connection with the operation of stapling the box at the corners it is to be noted that the clincher block and support are so constructed that the block may be placed beneath the overlapping portions at the corner of the box so as to securely seal it at this point. In order to accomplish this I 80 preferably construct the clincher block with rounded corners 31, 32 and inset the support portion 24 at 33 far enough to clear the edge of the inturned flap not only as the block is moved along the straight side of the box but 85 also at the corners thereof. Also this construction is such that the clincher block is supported to such an extent that it will, without any additional support beneath the block, take the impact as the metallic fastener is driven and clinch it beneath the underflap.

90 For sealing the box around its edge I start at A and continue along the four sides to A'. The last corner is sealed at D and the block then withdrawn from the box. In Fig. 11 I have shown how the clincher block is drawn between the side and end flanges 27 as the last staple is driven at D. In order to permit a ready withdrawal of the clincher block from the box at this last point, the block is rounded at 35 as shown in Fig. 2, so that as the box is drawn toward the operator the rounded edge of the block will find its way between the flanges 27 as indicated 100 in Fig. 11 and a staple driven at D after which the block is withdrawn from the box.

105 In describing the operation of the device I have shown one form of box and one method of sealing the cover thereof but it will be apparent that my invention is not limited to the sealing of any particular kind of box or sealing a box as in Fig. 7 in the particular way described. Also I contemplate employing my invention in other ways than that shown and described and do not desire to be limited to the exact structures disclosed but aim to cover all that which comes within the spirit and scope of the appended claims.

110 What I claim as new and desire to cover by Letters Patent is:—

115 1. In a stitcher for sealing fibre shipping boxes having an inturned flange around the edge of the box and a flat cover therefor, a stitcher head, a short clincher block for insertion beneath the flange, a support for the clincher block extending inwardly then rearwardly and angularly upwardly and then outwardly above and over the flange beneath 120

the cover and beyond the edge thereof whereby the block may be moved along beneath the flange so as to stitch the flange and cover along their overlapping portions, 5 said support being of dimensions and construction to be capable of clenching the staples without any additional support beneath the clincher block.

2. A machine for sealing a fibrous shipping case having a flap inturned around the outer wall with a flat cover while the contents of the case remain therein, comprising, 10 in combination, a driver for driving metallic fastenings, a rigid arm that extends transversely of and under the inner face of the

cover, a flat anvil support that extends from the arm forwardly and angularly downwardly then transversely beneath the flap on a side wall, and an anvil rigidly supported by the anvil support, means for rigidly supporting said arm and anvil from a position above the case being sealed, and means for actuating the driver to drive metallic fastenings through the adjacent edges of the cover and the flap on a side wall 25 as they are fed over the anvil.

In witness whereof, I hereunto subscribe my name this 3rd day of November, A. D. 1919.

EMIL HENNINGS.
